UNITED STATES PATENT OFFICE.

GEORGE N. PIFER, OF CLEVELAND, OHIO, ASSIGNOR, BY MESNE ASSIGNMENTS, TO
T. E. STEWART, TRUSTEE, OF CLEVELAND, OHIO.

AUTOMATIC PHOTOGRAPHIC APPARATUS.

1,270,203.

Specification of Letters Patent. Patented June 18, 1918.

Application filed June 30, 1916. Serial No. 106,741.

To all whom it may concern:

Be it known that I, GEORGE N. PIFER, a citizen of the United States, residing at Cleveland, in the county of Cuyahoga and

5 State of Ohio, have invented a certain new and useful Improvement in Automatic Photographic Apparatus, of which the following is a full, clear, and exact description.

This invention relates to certain improvements in automatic photographing machines, especially of the form shown in my prior Patent, No. 1,167,314, dated January 14, 1916, automatic photographing apparatus. More specifically considered, the invention relates to the ejector which ejects from the machine the finished picture, the object of the invention being to provide an ejector which is more satisfactory and durable than the ejector disclosed in said prior 20 patent.

In my prior patent above referred to, I have disclosed an automatic photographing machine, wherein the coin controlled slide mechanism causes the delivery of a sensitized plate from a plate magazine to the camera, and operates the switch which controls a motor utilized for operating in a predetermined order or sequence the various parts which are instrumental in causing a photographic impression to be made on the plate, the finishing of the plate into a positive picture, and finally, the ejection from the machine of the finished picture. In said apparatus, as soon as the photographic impression is made on the plate, the latter is delivered or caused to pass to a suitable disk-like support which is mounted upon the upper end of a vertical spindle, and is surrounded by a cup which normally bears 40 against the lower side of the camera box. The plate falls upon this support face upward, or in position to receive on the sensitized and exposed side different finishing solutions which are successively applied to 45 the plate. After each solution is applied to the plate, the spindle and support are spun by the motor to cause the solution to be forcibly and cleanly thrown therefrom, so that the next solution which is applied will not 50 be contaminated by that which had previously been applied. After certain solutions have been applied to the plate, the cup, plate, together with the support and spindle carrying the latter are lowered away from the 55 camera box, in order that a second exposure

may be made on the plate. Thereafter, finishing solutions are again applied until the picture is finished, whereupon it is ejected from the machine.

In the machine forming the subject matter of my prior patent, this ejecting means is carried in the cup, and consists of a pair of fingers formed by a suitable bent wire, which fingers are thrown upwardly so as to eject the picture by elevating the spindle 60 and support carrying the plate or picture. This ejector or ejecting means, while answering the requirements, is not satisfactory in all respects, especially as it has not the desired durability, in view of the fact that 65 it is subjected to the corrosive action of acidulated solutions used in the finishing part of the process.

The ejector forming the subject matter of the present invention overcomes the objection of the prior construction, and at the same time is extremely efficient and at all 75 times reliable.

My invention may be briefly summarized as consisting in certain novel details of construction and combinations and arrangements of parts which will be described in the specification and set forth in the appended claims.

In the accompanying sheet of drawings, 80 Figure 1 is a side view, with parts in section, of a part of the apparatus, showing my improved ejector, and the manner in which it is operated; and Fig. 2 is a sectional view along the line 2-2 of Fig. 1.

In the drawings, I have omitted the major portion of the apparatus, only that part which immediately concerns the ejector being shown, in order that unnecessary complications may be avoided.

In the drawing, 10 represents the lower part of the camera box, up against which is adapted to be pressed the cup or receptacle 11, which is adapted to be raised and lowered with respect to the camera box. 90 This cup has a hollow downwardly extending cylindrical shank 12, through which loosely extends a vertical spindle 13, to the upper end of which is secured a disk-like support 14, upon which a circular photographic plate 15 is adapted to rest, after the photographic impression is made in the camera, and during all the developing and finishing operations. As fully explained in my prior patent, as soon as the plate reaches 100

the support 14, certain finishing solutions are applied onto the plate from above, and after each solution is applied the plate is spun by spinning the spindle 13 to free the 5 plate of the solution. This is done by a motor (not shown) which at the proper intervals is operatively connected or placed in driving relationship with a grooved wheel 16, which is splined to the spindle 13. Just 10 beneath the support 14 on which the plate rests is a retainer or centralizer 17, having upstanding fingers which maintain the plate substantially centrally on the disk or support 14, while it is being spun by the motor. 15 This retainer has a pin and slot or spline connection with the spindle 13 so that the latter will rotate or spin the retainer, as well as the plate support 14 and plate 15, but may move upwardly relative to the retainer 20 and cup 11, as will later appear.

After one or more solutions are applied to the plate while on the support 14 while the latter is in its upper position in the light-tight chamber formed by the camera box 25 and by the cup 11, the cup, spindle, support 14, and partially finished plate 15 are lowered as a unit away from the camera box so that the portion of the sensitized plate not exposed by the photographic exposure made 30 in the camera is subjected to light for the second or reëxposure. The cup is thus lowered to the dotted position shown at 11^a, it being understood that in the lowered position just referred to, the cup 11, plate 15, 35 plate support 14, and retainer occupy the same relative positions as shown by full lines in the upper part of the figure. While in this position, different solutions are applied to the plate, including a developer and rinsing solution, each solution being thrown from the plate by spinning the spindle in the manner previously described. After the 40 different solutions have been successively applied and thrown from the plate, the cup 11 and retainer 17 are lowered to the point indicated by the dotted position 11^b. This time, however, the cup and retainer 17 only are moved *i. e.*, they are lowered with respect to the plate 15 and plate support 14, the plate 50 then standing clear of the cup and retaining fingers, as shown by dotted lines. The picture now being finished, is thence ejected from the machine through a suitable slot in the front wall of the casing, by the ejector 55 forming the subject matter of my invention, and this will now be described.

Before describing the ejector, it might be well to state briefly the manner in which the cup and other parts are raised and lowered, 60 with reference to the camera box. These parts are lowered by mechanism including a bell crank lever, mounted upon a shaft 18 driven by the motor previously referred to. This bell crank lever has a long arm 19, 65 which projects forwardly and is connected

by a pin and slot connection with the shank 12 of the cup 11, the shank having pins or lugs projecting therefrom and engaging in slots 19^a in the forked end of the arm 19. The bell crank is provided also with a 70 shorter arm 20, which is connected by a link 21 to an arm 22 pivotally mounted upon a shaft or rod 23, suitably supported in the frame of the machine. This arm 22 is provided with a finger or projection 24 engaging the edge or periphery of a cam disk 25, which is secured to and is rotated by the motor driven shaft 18 in the direction indicated by the arrow. This cam disk has an arc-shaped peripheral portion 25^a of such 80 radius that when engaged by the finger 24, the arm 19 is elevated and held in the position shown by full lines so as to elevate and hold the cup 11 up against the bottom of the camera box. This cam disk 25 is provided also with an arc-shaped peripheral portion 25^b of less radius than the portion 25^a, and as soon as the finger 24 rides from the portion 25^a to the portion 25^b, the arm 19 is lowered, bringing the cup, etc., to the position 11^a. Additionally, the cam disk is provided between the peripheral portions 25^a and 25^b with a recessed portion or depression 25^c, into which the finger 24 drops at the end of the picture finishing operation. When 95 the finger drops into the depression 25^c, the cup is lowered to the position 11^b, but the plate or now finished picture 15, and the support 14 are not lowered. At least they are not lowered any appreciable extent, for the reason that when they were previously lowered with the cup, to position 11^a, the lower end of the spindle was brought down to or substantially down to a fixed stop member 26. Consequently when the cup is 105 lowered the second time, the plate is not lowered, but stands clear of the cup and of fingers of the retainer 17.

When the cup and retainer are thus lowered to the position 11^b, in the manner just described, the picture is thrown or kicked laterally from the support 14, and out through a slot in the front wall of the casing by an ejector in the form of a leaf spring 27, which as will be observed, is outside of the 110 cup and in no danger of being corroded or otherwise affected by the solutions. This spring is attached at its lower end to the arm 19, and normally, it is substantially not 115 under tension, the spring occupying the 120 position shown by full lines when the cup is elevated to its normal position.

This spring, it will be observed, is provided with an upwardly projecting main portion 27^a and with an upper forwardly 125 projecting portion 27^b which extends at nearly right angles to the part 27^a, and which at its free forward end is provided with an upstanding portion or lip 27^c. In the angle between the portions 27^a and 27^b 130

is secured a pin 27^a which extends a short distance laterally of the spring, as shown in Fig. 2.

Now, as the arm 19 is lowered, so as to 5 lower the cup to the position 11^a, the end of pin 27^a in passing downward, engages and slides along the back of a suitably positioned and shaped stationary member 28 carried by a bracket 29, secured to a portion 10 of the frame shown at 30. As the pin slides downwardly along the back of the member 28, the upper part of the spring, that is the portions 27^b and 27^c are held from forward movement, with the result 15 that the spring is placed under tension. When the cup reaches the position 11^a, the pin is near the lower part of the stop member 28, and in fact occupies such position that on slight further lowering movement 20 of the spring, the said pin will pass downwardly beyond the lower part of the member 28. As soon as the cup is lowered to the position 11^b, the spring is released by the pin 27^b passing downward beneath the 25 stop member 28, whereupon the upper end of the spring ejector springs forward and the upturned lip 27^c in the forward movement strikes the finished plate or picture 15, and throws the same out through the 30 slot in the casing, the ejector being in substantially the position 27^b, when it engages and ejects the picture from the machine.

As soon as this is accomplished, the finger 24 rides out of the depression 25^e onto 35 the portion 25^a of the motor driven cam disk, whereupon the arm 19, cup, and other parts are elevated to normal position and the ejector is restored to the position shown by full lines. These parts are now in position 40 for a repetition of the photographing, finishing and ejecting operations, which have been described above.

Having thus described my invention, what I claim is:

45 1. In an automatic photographing apparatus, a camera box in which a photographic plate is adapted to be exposed, a finishing cup arranged adjacent the camera box and adapted to receive the plate after exposure, means for causing a relative movement between the cup and plate, and an ejector exterior to the cup for moving the plate away from the cup after such relative movement.

55 2. In an automatic photographing apparatus, a camera box in which a photographic

plate is adapted to be exposed, a finishing cup adjacent the camera box and adapted to receive the plate after exposure, means for shifting the cup and plate away from the 60 camera box and for subsequently causing a relative movement between the cup and plate, and an ejector exterior to the cup for moving the plate away from the receptacle after such relative movement. 65

3. In an automatic photographing apparatus, a camera box in which a photographic plate is adapted to be exposed, a cup adjacent the camera box and adapted to receive the plate after the exposure, means for causing the cup and the plate to move away from the camera box and for causing a relative movement between the cup and plate whereby the plate is temporarily positioned above the cup, and an ejector exterior to 70 the cup for moving the plate away from the cup. 75

4. In an automatic photographing apparatus, a camera box in which a plate is adapted to be exposed, a finishing cup adjacent the camera box and adapted to receive the plate after the exposure, means for lowering the cup and plate relative to the camera box and for subsequently lowering the cup relative to the plate, and an ejector 80 exterior to the cup for moving the plate laterally away from the cup on the occurrence of said relative movement. 85

5. In an automatic photographic apparatus, a receptacle adapted to receive a photographic plate, means for causing a relative movement between the plate and receptacle, an ejector comprising a spring for moving the plate away from the receptacle, and means whereby said spring is released so as to move the plate by said relative movement. 90 95

6. In an automatic photographing apparatus, a receptacle for a photographic plate, means for moving the receptacle, and for 100 causing relative movement between the receptacle and plate, means comprising a spring for moving the plate away from the receptacle, and means whereby energy is stored in the spring by said movement of 105 the plate and receptacle, and whereby the spring is released by said relative movement between the plate and receptacle.

In testimony whereof, I hereunto affix my signature.

GEORGE N. PIFER.
